UNITED STATES PATENT OFFICE

100,804

DESIGN FOR A RADIATOR FRONT

William Storrie, Providence, R. I., assignor to
Lewis R. Smith, trustee for Apco Mossberg
Corporation, a corporation of Rhode Island

Application April 21, 1936, Serial No. 62,228

Term of patent 7 years

To all whom it may concern:

Be it known that I, William Storrie, a citizen of the United States of America, residing in Providence, county of Providence, State of Rhode Island, have invented a new, original, and ornamental Design for a Radiator Front, of which the following is a specification, reference being had to the accompanying drawing, forming a part thereof.

Fig. 1 is a face view of a radiator front; Fig. 2

is an enlarged detail view of a plate forming the right half of the radiator front shown in Fig. 1; and Fig. 3 is a section on the line 3—3 of Fig. 2, of the same. The elements are shown as a unitary article.

I claim:

The ornamental design for a radiator front, substantially as shown and described.

WILLIAM STORRIE.
